UNITED STATES PATENT OFFICE.

LOT DAVIS, OF IRONTON, OHIO, ASSIGNOR TO WINN G. JACOB AND CHARLES G. SHULZE, OF CIRCLEVILLE, OHIO.

VEHICLE-WRENCH.

SPECIFICATION forming part of Letters Patent No. 710,847, dated October 7, 1902.

Application filed June 25, 1902. Serial No. 113,166. (No model.)

To all whom it may concern:

Be it known that I, LOT DAVIS, a citizen of the United States, residing at Ironton, in the county of Laurence and State of Ohio, have 5 invented certain new and useful Improvements in Vehicle-Wrenches; and I do hereby declare the following to be a full, clear, and exact description of the invention, such as will enable others skilled in the art to which it 10 appertains to make and use the same.

My invention relates to improvements and means for removing and replacing the nuts upon axles of carriages, wagons, or the like; and it consists in a device formed with a nut- 15 engaging portion and a hub-engaging portion, the hub-engaging portion being adapted to be clamped upon the periphery of the hub of a wheel, so that by turning the wheel the nut will be forced to move with the same 20 and may be screwed or unscrewed, as desired.

It also consists in certain other novel constructions, combinations, and arrangements of parts, as will be hereinafter fully described 25 and claimed.

In the accompanying drawings, forming a part of this specification, Figure 1 is a perspective view of a wrench mechanism constructed in accordance with the present in- 30 vention. Fig. 2 is a vertical central sectional view through the wrench as applied to the hub of a wheel and engaging the nut which holds the same upon an axle. Fig. 3 is a detail view showing a different way of construct- 35 ing the clamping portion of the wrench mechanism.

The present invention is designed to supply a mechanism which may be employed for readily removing the nuts of vehicles from 40 their axles, the said device being capable of such engagement with the hubs of the vehicle-wheels that when the wheel is turned the nut will be forced to move with the same for turning the nut off or upon the threads of 45 the axle-spindle.

I am aware that devices of a similar character have been employed; but the present invention affords a very efficient means of securing the wrench mechanism to the hub 50 of a wheel, and while the device is exceed-

ingly simple in structure it is extremely effective for operating upon the nut of a vehicle-axle without marring or in any way disfiguring the hub of a wheel or the finished surfaces of the same. 55

The device forming the subject of this invention is made up of a nut-engaging portion 1 and a hub-clamping portion 2. The nut-engaging portion is preferably a closed sleeve, as 3, which is made of suitable size 60 to fit upon the nut to be turned. Upon opposite sides of the said sleeve 3 are hinged swinging arms 4, which are capable of being folded along the sides of said sleeve upon opposite sides of the nut. One of the pivoted 65 arms 4 is secured to the clamp 2. The clamp 2 may be made in the form of a circle or a flat ring, as found most desirable, and is made of sufficient size to receive the end of the wheel-hub to be operated upon. The hinged 70 arm 4, which is disconnected from the clamp 2, is arranged so that its free end may be brought within the ring of the said clamp, and a screw or bolt, as 5, is mounted in a screw-threaded aperture 6, formed in the 75 clamping-ring at a point opposite the attached end of the opposite pivoted arm 4. When the free arm 4 is folded within the clamping-ring, its free end is brought opposite the end of the clamp-screw 5, so that by 80 turning the said screw the said free arm 4 can be forced against the hub of the wheel. Of course at the same time the opposite side of the ring 2 and the pivoted arm which is secured to the same are drawn against the said 85 hub. In this manner the wrench mechanism can be firmly clamped to the hub of the wheel while the nut-engaging sleeve 1 is in proper position to inclose the nut which holds the wheel upon the axle. With the parts in this 90 position the nut can be readily turned upon the threads of the axle-spindle by turning the wheel itself upon the axle. The free end of the free arm 4 is preferably formed with a recess or depression 7 to receive the end of 95 the clamping-screw. This prevents the chance of the screw slipping upon the said arm when the device is being clamped upon the hub of a wheel.

While I have shown in Figs. 1 and 2 of the 100

drawings the clamping mechanism as formed of a continuous ring, yet it will be evident that I might form a clamp of a half-ring or C-shaped iron, as shown at 8 in Fig. 3. In 5 this instance the clamp would be attached to the pivoted arm 4 in the same manner as the ring above described, and the clamp-screw at the other end of the half-ring will be in position to engage the other arm 4 in the same 10 manner as above set forth. When forming the clamp in this manner, I prefer to hinge the same to one of the arms 4, as shown at 9 in Fig. 3. With the clamp formed in this manner the semicircular iron 8 may be turned 15 back upon its hinge out of the way while the nut-engaging sleeve is being put into position. The semicircular clamp is then placed around the end of the hub and the clamp-screw tightened, as above stated.

20 Among other advantages possessed by the mechanism just described may be mentioned the fact that the parts can be so clamped upon the hub of a wheel as to avoid any slipping with respect to the same, and 25 yet not run any risk of scratching or marring in any way the finished surfaces of the wheel-hub. I find in practice also that a clamp which surrounds an article can be made to engage the same with greater firmness, as a 30 rule, than clamps which are placed within a cylindrical article.

It will be observed that the manner of hinging the arms 4 to the nut-sleeve facilitates the placing of the wrench mechanism in position or removing the same. I also contemplate lining the inner surfaces of the said pivoted arms 4 and any portion of the clamping-ring which may engage the hub of a wheel with some soft or smooth material, so as to 40 further avoid the scratching or marring of the finished surfaces of the hub.

I wish it to be understood that any minor changes which may be made I regard as within the scope of the invention.

45 Having thus fully described my invention,

what I claim as new, and desire to secure by Letters Patent, is—

1. A wrench mechanism for nuts of vehicle-wheels, comprising a nut-engaging portion and a clamping-ring, a hinge rigidly secured 50 to the clamping-ring at one end and carrying the nut-engaging portion at the other, a second hinge mounted on said nut-engaging portion having a free end, such free end adapted to be engaged by a screw seated in the clamp- 55 ing-ring, substantially as described.

2. A wrench mechanism for the nuts of vehicle-wheels, comprising a nut-inclosing sleeve, hinged arms secured thereto, a hub-inclosing ring carried by one of said arms and 60 adapted to be folded over the other arm and around a hub of a wheel for securing the said wrench mechanism to such wheel so that it may be turned thereby, substantially as described.

3. A wrench mechanism for the nuts of vehicle-wheels, comprising a sleeve for engaging a nut, arms hinged upon opposite sides of said sleeve and adapted to be folded back upon the same, a clamping-ring secured to one of 70 said arms, and a clamp-screw carried by said ring and arranged to engage the other arm and force the same against the hub of the wheel, substantially as described.

4. A wrench mechanism for the nuts of vehicle-wheels, comprising a clamping-ring, a nut-engaging member hinged to said clamping-ring, a hinged arm carried by the said nut-engaging member and adapted to be engaged by a set or thumb screw carried by the 80 clamping-ring for binding the latter against the hub of the wheel, substantially as described.

In testimony whereof I hereunto affix my signature in presence of two witnesses.

LOT DAVIS.
